(57) CLAIM

The ornamental designs for a combined game coin and package, as shown and described.

DESCRIPTION

FIG. 1 is a perspective view of the combined game coin and package of the present invention.

FIG. 2 is a perspective view of an alternate embodiment of the combined game coin and package of the present invention.

FIG. 3 is a rear view of the combined game coin and package of FIGS. 1 and 2.

FIG. 4 is a right side view of the combined game coin and package of FIGS. 1 and 2, the left side view being identical thereto.

FIG. 5 is a top view of the combined game coin and package of FIGS. 1 and 2; and,

FIG. 6 is a bottom view of the combined game coin and package of FIGS. 1 and 2.

In the drawings, the broken lines are for the purpose of illustrating environment only and form no part of the claimed design.
